**FORMATION TESTER FOR DRILLING WITH
CASING**

John E. Ortloff, Tulsa, Okla., assignor to Esso Research and Engineering Company, a corporation of Delaware

Application November 29, 1954, Serial No. 471,710

3 Claims. (Cl. 166—115)

This invention concerns a novel formation tester for use when employing the so-called drilling with casing technique. The present invention is intended to provide means for determining the nature of well fluids from a well bore without necessity for removing casing which has been placed in the well bore. Apparatus is provided which may be suspended on a wire line to be lowered downwardly through the casing of a well. The tester of this invention is supported from the lower termination of the casing so as to extend beneath the casing. Fluid ports are provided to permit access of well fluids into a sample chamber of the arrangement. The formation tester may then be recovered by use of a wire line and the trapped fluid sample can be recovered for examination at the surface of the earth.

At the present time, a great deal of work is being carried out to develop an attractive technique for "drilling with casing." In this technique, the objective is to employ large diameter casing rather than smaller diameter drill pipe in the operation of all drilling steps. In drilling with casing, a retractable drill bit is employed of such a nature that the bit can be lowered through the casing on a wire line to be latched in drilling position at the bottom of the casing. Expansile cutting edges of the drill extend outwardly when the drill is latched in position so as to drill a borehole somewhat greater in diameter than the casing. In this arrangement, the drill bit can be retrieved by a wire line to be pulled upwardly through the casing when it is necessary to service or replace the drill bit. Consequently, as drilling proceeds, additional lengths of casing are added without any necessity for removing the casing from the borehole.

To secure the full benefits of drilling with casing, it becomes attractive to develop means for conducting all normal borehole operations, as well as drilling, without necessity for removing the casing from the borehole. For example, in normal drilling operations, so-called formation testers are frequently employed during drilling to determine whether or not there is any production of oil or other fluids at different levels in a borehole. Conventional formation testers are adapted for use on a drill string and are not adaptable for testing formations without removing the entire drill string from the borehole. It is therefore the principal objective of this invention to provide a formation tester which can be operated to sample well fluids without necessity for removing the well casing.

The advantageous features and nature of this invention can be fully understood by reference to the attached drawings. The drawings illustrate a preferred embodiment of the invention in cross-sectional elevational detail.

Figure 1 illustrates the entire formation testing arrangement in operative position in a casing at the bottom of a borehole;

Figure 2 illustrates a shear pin arrangement which is preferably employed in the apparatus of Figure 1 during lowering of the formation tester into the casing; and

Figure 3 illustrates the sample chamber of the formation tester and the spearhead provided for the wire line

2

operation of the apparatus, and constitutes an upper continuation of the apparatus shown in Figure 1.

For the purposes of this invention, it is assumed that drill hole 2 is cut into the earth by a drilling with casing technique. Thus, a retractable drill bit having extensible cutting teeth, is operated from the casing extension sub 3 so as to drill the borehole 2. When drilling has proceeded to a depth at which it is desired to conduct a formation test, the retractable drill bit is recovered from the casing sub 3 by means of a wire line. A drill bit is then lowered into the casing to drill a small diameter pilot hole 4 beneath the larger diameter borehole 2. A conventional retractable drill bit may be used to drill the pilot hole providing that the cutting teeth of the drill bit are held in a non-expanding position so as to drill a borehole substantially equal to the inner diameter of the casing 1. This drill bit is then removed from the casing by means of a wire line and the tool of this invention may then be employed to conduct a formation test in the pilot hole 4. Further details of the techniques used for drilling the borehole 2 and the pilot hole 4 by a drilling with casing technique are not considered necessary for an understanding of this invention. As indicated, drilling of the borehole 2 and the pilot hole 4 may be carried out by known and conventional techniques.

The apparatus of this invention includes all of the mechanical elements illustrated in the drawing within the casing 1 of which sub 3 is an extension. Thus, 30 the apparatus generally includes a spearhead 5 as the uppermost section surmounting a cylindrical chamber 6 which is provided to contain fluids obtained during formation testing. The central portion of the formation tester includes upper and lower latches 7 and 8 for locking the formation tester in the casing. The lowermost portion of the formation tester is provided with a packer arrangement 9 for sealing the formation tester in the pilot hole 4. Fluids which may be present in the strata communicating with the pilot hole 4 may obtain access to the sample chamber 6 through ports 10 flowing upwardly in the interior of the apparatus past the production valve 11 into the sample chamber 6. With this general identification of the elements of the formation tester, the specific nature of these elements and their particular design can be appreciated.

In order to provide a suitable latching arrangement for the formation tester, a central cylindrical portion of the tester identified by numeral 12 is machined to have an upper termination of reduced diameter indicated by 45 numeral 13. Reduced section 13 is fabricated to have a smaller outside diameter than the remainder of cylinder 12. The lower termination of outer cylindrical element 17, to which the upper cap portion 21 of the sample chamber 6 is threadably attached, is similarly machined to have an inner bore 14 adapted to fit over reduced section 13 of cylinder 12 in a reciprocal sliding relationship. Sealing means 23 is provided to maintain a fluid tight condition between element 17 and reduced section 13 as illustrated. Cylindrical element 17 and portions 12 and 13 in assembled condition are adapted to be lowered and moved vertically within the casing extension sub 3 as shown.

Upper latching dogs 7, two of which are illustrated, are pivoted by means of pins 47 in recesses 15 of cylindrical element 12. Slots 25 are provided in the outer cylindrical element 17 so as to generally register with the position of the latches 7. Thus, each latch 7 may be placed in a position such that it can pass through slots 25 in cylindrical element 17 to engage grooves 20 in casing sub 3. Each of the slots 25 is spaced from the bottom edge or end of cylindrical element 17 by what

may be termed as a lower lip portion 16, at all times positioned somewhat below the latches 7.

In this arrangement, when the weight of the formation tester is suspended on a wire line, element 17 will slide upwardly with respect to element 12 so that the lip 16 of the slot in element 17 will be forced upwardly against the tooth 50 provided on latch 7. This will have the result of forcing the latch 7 into a retracted position within its slot 15. However, when the weight of the formation tester is taken off the wire line as will be described, element 17 can slide downwardly with respect to element 12, permitting the latch 7 to extend outwardly to the position illustrated.

Lower latching elements 8 which are pivoted on pins 48 in recesses 26 of cylindrical element 12 are also provided. Both latches 7 and 8 are biased outwardly by means of bowed springs 18.

The manner in which these elements operate can now be fully appreciated. When the formation tester of this invention is to be employed, the casing extension sub 3 will be lifted somewhat above the floor of the borehole 2. A wire line will then be attached to spearhead 5 of the formation tester, and the tester will be lowered downwardly through the casing. As described above, during the lowering operation, the upper latches 7 will be held in a retracted position. Consequently, the formation tester may be dropped downwardly through the casing until the lower latches 8 contact the shoulder of the lower groove 19, machined in the lower portion of casing 3. Springs 18 forcing latches 8 outwardly into groove 19 will result in locking the formation tester against further downward movement. Consequently, the weight of the formation tester will be transferred from the spearhead 5 to the latches 8. This will permit cylindrical element 17 to slide downwardly with respect to cylindrical element 12 permitting upper latching dogs 7 to extend outwardly into the upper groove 20 provided in casing sub 3. If desired, the wire line can then be removed from spearhead 5. When the casing 1 and the casing sub 3 are then lowered in the borehole, the extending termination of the formation tester will be brought into contact with the bottom of pilot hole 4. A portion of the weight of the casing 1 and casing extension sub 3 can then be forced downwardly on the formation tester through the upper latching dogs 7. In this manner, latches 7 and 8 cooperate to lock the formation tester with respect to both upward and downward movement relative to the casing.

The lower termination of cylindrical member 12 is attached to nest over an upper termination of the lowermost cylindrical element 24. Cylindrical members 12 and 24 are therefore arranged for telescopic sliding movement. A packer 9 is circumferentially arranged about the joint between nesting elements 12 and 24. The uppermost portion of packer 9 is sealed in element 12 while the lowermost portion of packer 9 is sealed in element 24. Consequently, when the lower portion of the formation tester is forced against the bottom of the pilot hole 4, cylindrical element 24 will be forced upwardly with respect to cylindrical element 12, causing packer 9 to be forced outwardly against the wall of pilot hole 4. The lower portion of the formation tester will then be sealed in pilot hole 4 so as to exclude drilling mud existent in borehole 2.

Fluid which may flow from strata adjacent pilot hole 4 may gain access to the interior of the formation tester through the ports 10. As illustrated, the central portion of all elements of the formation tester are cut out to provide a central passage or channel extending upwardly to the sample chamber 6. It is essential to prevent flow of fluid to the sample chamber until the formation tester is in operative position at the bottom of pilot hole 4. For this reason, a valve 27 is provided in the central passage. As illustrated, valve 27 may simply comprise a rod-like valve member fixed to or integral with the lower

termination of cylindrical member 24. Valve 27 will be seated against valve seat 28 so as to prevent fluid flow past the valve as long as cylindrical element 24 is at its lower limit of movement with respect to cylindrical element 12. Thus, while the formation tester is being lowered through the casing, the weight of the elements of the apparatus will tend to cause valve 27 to maintain its closed position. On the other hand, the resistance of drilling mud in the borehole will tend to force cylindrical element 24 upwardly as the tool is lowered, which would tend to open valve 27. To prevent the possibility of valve 27 opening, before the formation tester is in sampling position, a shear pin 30 may be passed through valve 27, locking it in cylindrical element 12 as shown in Figure 2. Shear pin 30 is adapted to break when the casing is lowered so as to force the bottom of the formation tester against the bottom of pilot hole 4. Breakage of the shear pin will permit valve 27 to open at the same time that packer 9 is forced against the wall of the borehole 4. Fluid may then flow through ports 10 upwardly past valve 27 and into sample chamber 6.

When a sample of the well fluids has been obtained in this manner, the formation tester can be retrieved through the casing by affixing a wire line to spearhead 5. In the retrieving operation, the casing 1 and casing sub 3 will be lifted somewhat off the bottom of the borehole causing cylindrical element 12 to slide upwardly with respect to cylindrical element 24 permitting packer 25 to collapse. This will also tend to cause valve 27 to seat, so as to seal the sample fluid in sample chamber 6. To secure positive closure of valve 27, a spring 33 may be positioned about the valve stem bearing against lip 34 of cylindrical element 12. Spring 33 will thus positively force closure of valve 27 when casing sub 3 is lifted in the borehole.

The formation tester can be retracted through the casing automatically when the wire line attached to spearhead 5 is pulled upwardly. Lifting force applied to spearhead 5 will cause the upper cylindrical element 17 to slide upwardly with respect to element 12, the lips 16 of the slots provided in cylindrical element 17 will be forced upwardly against the latching dogs 7 to force these into a retracted position out of engagement with the groove 20 of the casing 3. The entire formation tester can then be pulled upwardly through the casing and the trapped fluid sample can be examined at the surface of the earth. It is convenient to provide a manually operated valve 37 in the sample chamber 6 to permit the trapped fluids to be bled out of the sample chamber.

As described, the essential and operative elements of the formation tester of this invention include the following features. First, retractable latching means are provided to positively lock the formation tester in the lower termination of a casing. These latching means are so positioned that when the formation tester is locked at the lower termination of the casing, a portion of the formation tester extends below the casing into a small diameter pilot hole. Packing means are provided about the lower portion of the tester so as to seal the formation tester in the pilot hole 4. Ports cut through the formation tester below the packer provide access for fluids permitting fluids to flow upwardly into an interior sample chamber of the formation tester. A valve is employed to prevent flow of fluid into the sample chamber until the packer has been operated to seal the formation tester in the pilot borehole.

In the preferred embodiment of this invention in which the specific elements described are employed to provide the essential functions identified, a number of advantageous features are appreciated. For one thing, the formation tester is adapted to positively lock in the lower termination of the casing while at the same time, means are provided to permit the positive withdrawal of the formation tester from the casing. The valve arrangement described provides fool proof means to eliminate entrance of drilling mud into the sample chamber of

the apparatus, while the tool is being lowered to formation testing position. Again this valve causes sampled fluid to be trapped in the sample chamber at the pressure existent in the borehole when sampled. An additional feature of the apparatus described is the simplicity of the packing arrangement which may be used to seal the formation tester in the borehole during a formation test.

The patentable novelty of the invention described is defined by the following claims.

What is claimed is:

1. A formation tester adapted to be used when drilling with casing which comprises in combination an elongated cylindrical casing extension sub secured to the lower end of the casing within a bore hole, an elongated cylindrical body portion, an outer cylindrical element surrounding an upper portion of the cylindrical body portion in a vertical sliding relationship, means for lowering said outer element, said cylindrical body portion and said lower element in an assembly form within said sub, retractable upper latching means and lower latching means pivotally mounted on said cylindrical body portion and arranged to engage upper and lower recesses within said casing sub, said upper latching means engaging said upper recesses through ports in said outer cylindrical element when said outer cylindrical element moves downward relative to said elongated cylindrical body portion, said lower latching means being arranged to engage said lower recesses when said lower cylinder element moves vertically upward relative to said cylindrical body portion, a sample chamber disposed within said assembly, packing means fixed to said elongated body portion and said lower cylindrical element and arranged to be expanded against the wall of the bore hole in response to vertical upward movement of said lower cylindrical element relative to said body portion, at least one port providing fluid access from the bore hole at a point below said packing

means to a point within said sample chamber and valve means intermediate said port and said sample chamber actuatable to seal fluid within the sample chamber.

2. An apparatus as defined in claim 1 in which the valve means is a spring loaded normally closed valve arranged to open when the lower cylindrical element moves vertically upward relative to the cylindrical body portion a distance sufficient to expand the packing means.

3. A formation tester for use beneath a casing suspended in a bore hole comprising in combination a cylindrical extension sub secured to the lower end of the casing, an elongated cylindrical body portion having a central chamber adapted to move vertically within and to extend partially below said sub, said body portion including two cylindrical elements maintained in nesting sliding relationship including ports in the outermost of said elements, the inner element being provided with pivotally mounted latching dogs retractably arranged to move through the ports in the outer element and to engage with recesses in the inner surface of the casing extension sub, packing means mounted on said cylindrical body portion and arranged to seal the annular space between the body portion and the wall of the bore hole below the sub, fluid ports arranged in the body portion below said packing means and arranged to provide fluid access from the bore hole into the central chamber, and valve means arranged to seal bore hole fluid within the interior chamber.
